UNITED STATES PATENT OFFICE

JOSEPH ZUBATY, OF FLINT, MICHIGAN, ASSIGNOR TO A C SPARK PLUG COMPANY, OF FLINT, MICHIGAN, A COMPANY OF MICHIGAN

SPEEDOMETER TEMPERATURE COMPENSATOR

Application filed September 29, 1928. Serial No. 309,283.

This invention relates to measuring instruments and has been designed particularly as an improved speedometer for use on motor vehicles.

5 An object of the invention is to render the readings of such an instrument accurate at all temperatures.

Another object is to attain the desired end by the use of temperature correcting means 10 employing no movable parts.

As a further object the invention is designed for use particularly with a specific type of speedometer wherein all supporting parts are made from inexpensive stampings, 15 and wherein a guard is used around the speed cup to support certain of the elements of the instrument, this guard constituting a convenient member to co-operate with the compensator in making an efficient magnetic 20 shunt.

Other objects and advantages will be understood from the following specification.

In the drawings:

Figure 1 is a vertical sectional view of a 25 speedometer with the invention applied, parts being shown in elevation, parts broken away, parts in section;

Figure 2 is a rear elevation of Figure 1 with the case removed the compensator units 30 being shown in position; and

Figure 3 is a top plan view showing the case in section and the mounting plate in elevation.

The speedometer shown in the drawings is 35 housed in a casing 9. To this casing is secured a mounting plate 10 which supports the odometer unit shafts 11 and 12. These shafts are journaled between side wings 13 and 14, stamped and angularly turned from 40 the mounting plate 10. The odometer wheels are assembled on the shafts 11 and 12 and are driven in the well-known manner by star pinions. These star pinions are not illustrated, being preferably within the 45 contour of the figure wheels which later are provided in a well-known way with internal gear members. The star pinions are supported by stampings 15 which are suitably secured and held stationary by means of 50 shafts 16 and 17. Shaft 16 is journaled be-

tween the wing members 13 and 14, and shaft 17 is journaled between tongues 18 and 19 struck out and angularly turned from the mounting plate 10.

Secured to the mounting plate and supported by it is a speedometer mechanism supporting frame 20. This frame also is formed from a stamping. Mounted between tongues 21 and 22 is a drive bushing bearing 23 in which is journaled the drive bushing 24.

55 The lower end of this bushing is drivingly connected to the main flexible cable 25. The driving connection may include non-circular portions, not shown in the drawing, or other convenient means may be employed. The 60 drive bushing projects upwardly from the bearing and formed on the bushing is an eccentric or cam 26, upon which is journaled a pawl 27 which drives the double reduction ratchet wheels 28, these having a known form 70

of construction, which ratchet wheels in turn drive the gear 29, the latter meshing with gear 30 to drive the season mileage recording figure wheels 31 on shaft 11. The trip wheels 32 on shaft 12 are driven by gearing between shafts 11 and 12, including an intermediate gear preferably mounted on shaft 111. As this construction is well-known, it is not fully illustrated.

75 Above the upper end of the drive bushing is a guard member 33, preferably of steel. This guard member is mounted upon and secured to angularly turned horizontal wing members 34 and 35 constituting a part 80 of frame 20 which, in this way, acts as a base for said guard. The guard is bolted to said base by means of fastening means 36 which pass through suitable openings in the wings 34 and 35 and also through outwardly turned ears 37 and 38 stamped from member 33.

85 Fixedly mounted upon the upper end of the drive bushing by means of riveting over as at 39 is a rotating magnet 40. This magnet is cross-shaped, as shown by dotted lines 90 in Figure 3, and there are members 41 which bridge the magnet gaps and are suitably riveted to the magnet.

95 A speed cup 42 is centrally centered by means of the usual speed cup spindle 43.

100

This spindle may be journaled in the usual way, preferably its lower end being received in bearings in the end of drive bushing 24 and its upper end extending through suitable bearings in the guard member 33. As this is a conventional method for mounting the speed cup spindle, it is not illustrated in detail.

5 Above the guard 33, the upper end of the 10 spindle is provided with a hub member 44 to which is fixed one end of a coil hair spring 45, the other end of the spring being fixed to an upwardly projecting ear 46 stamped from the guard 33.

15 For the purpose of limiting the rotation of the speed cup, an ear 47 is stamped from member 33 and angularly turned downwardly to project into the path of a similarly stamped ear upwardly directed from the speed cup.

20 A ferrule 48 is employed at the point of entrance of the flexible driving cable 25. To the ferrule at the lower end is fixed an armoring cable 49 for protecting the rotating cable 25. Preferably, although not shown in 25 the drawing, the drive cable 25 will be provided with a bushing, the bushing having a flange to engage a suitable shoulder within the ferrule whereby the backward movement of the cable 25 is prevented and the driving 30 connection between parts 25 and 24 is maintained. This structure, not constituting a part of this invention, is not illustrated.

35 Fixed to the ferrule 48 is a clamping member 50 which is bifurcated at its end remote from the ferrule. The bifurcated end yokes over a fastening screw 51 and is securely fastened and clamped thereon by means of a thumb nut 52.

40 Projecting downwardly from part 20 is a tongue 53. This tongue acts as a support for a reset stem 54. The reset stem does not constitute any part of this invention and its relation to the trip wheels is as usual in odometer mechanism and need not be more fully 45 described.

45 Fixedly mounted to the guard 33 by means or riveting is a temperature compensator 55. This compensator projects downwardly and is angularly bent to project towards the magnet and then again angularly turned so that its end is in close proximity to the magnet and, consequently, directly within the magnetic field.

50 Because of the composition of the metal member 55, which consists of a nickel-copper alloy having the property of magnetic conductivity at low temperatures and changing to practically no conductivity at high temperatures, magnetic current will be shunted 55 or otherwise diverted to the steel guard 33 through the member 55 at low temperatures due to the increased conductivity of the member 55 to thereby decrease the magnetic flow or flux of the magnetic field established by the rotating magnet 40. On the other hand,

the flow or flux of the magnetic current in the magnetic field will be increased proportionately to the low conductivity of member 55 at high temperatures, thereby retaining the magnetic flux within the magnetic field. 70 By this means, the effects of temperature changes are offset and the instrument rendered accurate at all temperatures.

75 A member 56 is shown in the drawing riveted to frame 20 and also extended to a position adjacent the magnet 40. This member 56 is also a nickel-copper alloy and its function is precisely the same as that of member 55. It will be understood that if parts 20 and 33 are both of steel and if it be so desired, both members 55 and 56 may be used. However, under such circumstances, it is believed that one such member, 55 or 56, will be sufficient. It should be further stated that in the event that part 33 or 20 should be 80 of other than magnetic material, one only of the members 55 or 56 will be used, the member used being associated with that part, 33 or 20, which is of magnetic material.

85 By the construction above outlined, there 90 has been produced a speedometer of very simple design in which the most desirable features of speedometers heretofore known have been incorporated. The instrument is rigid, sturdy and durable and has, nevertheless, been made of stampings and without any expensive die cast parts. The main mounting plate 10 directly supports the odometer mechanism and the speedometer supporting mechanism, also a stamping, is secured to the 95 first frame.

100 The different operating units have been combined in a way to simplify the structure without decreasing its efficiency—in fact, the 105 efficient operation of the unit as a whole has been increased. The assembly is rendered very compact and reduced in weight. There is a substantial reduction in machining operations, particularly in the relatively expensive operations such as die casting and worm gear cutting. The worm gearing heretofore used in speedometers has been altogether eliminated and the ratchet drive is directly mounted on the driving bushing, this being made possible with the use of the double reduction ratchet mechanism. The magnet is directly mounted on the bushing, thus dispensing with the rotor. There is a simplified mounting means for the speed cup in which the conventional jewel frame is displaced and the guard member which supports the temperature compensator is used. This guard member also affords the means for connecting the end of the hair spring.

110 It is thus seen that by providing stampings for all the frame members, such as mounting plate, supporting frame and guard unit, as well as the casing itself, a speedometer is produced having uniform strength which is carried throughout as a 115 120 125 130

unit. There are less parts to get out of order and the mechanism is greatly simplified. There is, in consequence, a high degree of efficiency and accuracy which results are obtained with a considerable lower production cost in manufacture and assembly.

5 I claim:

In a measuring instrument, a rotary magnet, a rotary speed cup surrounding said magnet, a cup-shaped guard of magnetic material surrounding said speed cup, a temperature compensator having its magnetic conductivity decreasing with increasing temperatures, said compensator being secured to said guard 10 and extended to a position adjacent said magnet.

In testimony whereof I affix my signature.

JOSEPH ZUBATY.
